FIG. 6.

UNITED STATES PATENT OFFICE.

ALBERTO CIMOROSI, OF BUFFALO, NEW YORK.

SIGNALING-TORPEDO.

1,285,040.

Specification of Letters Patent. Patented Nov. 19, 1918.

Application filed June 30, 1917. Serial No. 178,008.

To all whom it may concern:

Be it known that I, ALBERTO CIMOROSI, a subject of the King of Italy, residing at Buffalo, in the county of Erie and State of New York, have invented certain new and useful Improvements in Signaling-Torpedoes, of which the following is a specification.

My invention consists of an improved form of signaling torpedoes, such as are used on railroad tracks for the purpose of notifying an oncoming train that there is danger ahead.

Signaling torpedoes of this type are attached to the head of the rail, and as they are engaged by the wheels of the train, will explode, thereby producing a noise which forms the signal.

Prior to my invention, the construction of these torpedoes was such that in many instances the wheel of the train instead of running over and exploding them would merely push them off the track. The reason for this was that the torpedo projected so far above the track as to provide a shoulder or upwardly projecting edge which, when the wheel engaged it, would merely act as a means for deflecting or sliding the torpedo from the track prior to the time when the wheel should pass over the explosive compound within the torpedo.

One of the objects of my invention is to provide a torpedo with a relatively thin portion which extends sufficiently beyond the explosive portion of the torpedo that the wheel of the train will be compelled to ride on said thin portion, and when once thereon, will effectively bind or press the torpedo to the track and compel the explosive portion to remain thereon until the wheel reaches and runs over it.

Another object of my invention is to provide my improved torpedo with mechanism for retaining the explosive within the body, the retaining means being such that it may be easily removed or inserted, but when once in place, will act to effectively retain said explosive within the body portion.

A still further object of my invention is to so construct my improved torpedo that it may be quickly assembled and may be manufactured at a comparatively low cost.

These objects, and other advantageous ends which will be described hereinafter, I attain in the following manner, reference

being had to the accompanying drawings in which—

Figure 1 is a top plan view of my invention.

Fig. 2 is a side elevation of my improved torpedo as shown in Fig. 1, and illustrated in connection with a rail.

Figs. 3 and 4 are sections taken on the lines *a—a* and *b—b* respectively, of Fig. 1.

Fig. 5 is a top plan view of a modified form of my invention, and

Fig. 6 is a section taken on the line *c—c* of Fig. 5.

Referring to the drawings, 1 is a base plate or body portion made of thin sheet material of any suitable character which can be easily cut and bent into shape. This base has an upwardly projecting recess 2 formed therein by stamping or other means, and this recess provides a housing for the explosive material 3, the latter being confined within the recess by means of a cap 4 having an up-turned annular flange 5.

The explosive material and cap are of such size as to completely fill the recess 2, the lower face of the cap 4 being flush with the under face of the oppositely tapered end extensions 6, 6, of the base 1. These extensions 6 may be of any length desired, and by the above mentioned construction are of a single thickness of sheet metal and designed to be engaged by the wheel of a train prior to the engagement of the wheel with the raised portion 7 which provides said recess 2.

A retaining strip 8 made of flexible metal or other material extends through slots 9 formed in the sheet base 1, and has a portion 10 which extends under the cap 4 so as to retain the latter within the recess 2.

The extensions 6 are preferably made in an angular tapered formation as shown in Fig. 1, and are designed to lie flat and longitudinally on the head or tread surface of the rail.

Fig. 2 illustrates the wheel 11 of a train in engagement with and riding one of the extensions 6, and it will be understood that the pressure exerted upon said extension 6 will prevent its removal from the track after the wheel has once engaged it, thus compelling the wheel to ride over the portion 7 and explode the explosive material 3.

In the form of my invention shown in Figs. 5 and 6, instead of having the retain-

5 ing members 8 extend through slots 9, I secure the retaining strips 12 to the face of the sheet base portion 1 by solder or other means. In this instance, the cap 4 is retained within the recess 2 by means of sealing wax, paraffin, or other sealing medium as shown at 13 in Fig. 6.

10 While I have described my invention as taking a particular form, it will be understood that the various parts of my invention 15 may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:

20 1. A torpedo having a body plate provided with an extension adapted to be laid longitudinally upon the tread surface of a rail, said body having a recess formed in its bottom; explosive material contained within 25 said recess; a cap inserted in said recess to form an undercover for the explosive material, said portion having slots therein at opposite sides of said recess; and a retaining

strip extending through said slots and under said cap, said retaining strip providing means whereby the base plate can be secured to the rail, substantially as described.

2. A torpedo having a comparatively thin body plate of single thickness material provided with an extension adapted to be laid longitudinally upon the tread surface of a rail, said extension tapering to a point from a portion of relatively great width, said portion having a recess formed in its bottom; explosive material contained within said recess; a cap inserted in said recess to form an undercover for the explosive material, said portion having slots therein at opposite sides of said recess; and a retaining strip extending through said slots and under said cap, said retaining strip providing means whereby the base plate can be secured to the rail, substantially as described.

30 In testimony whereof I have signed my name to this specification in the presence of two subscribing witnesses.

ALBERTO CIMOROSI.
